UNITED STATES PATENT OFFICE.

VAN BUREN L. HOYT, ANDREW SAROSI, AND ADNEY WOOSTER, OF STAMFORD, CONNECTICUT.

RAIL-CHAIR.

1,054,553.

Specification of Letters Patent. Patented Feb. 25, 1913.

Application filed April 22, 1912. Serial No. 692,352.

To all whom it may concern:

Be it known that we, VAN BUREN L. HOYT, ANDREW SAROSI, and ADNEY WOOSTER, all citizens of the United States, residing at 5 Stamford, in the county of Fairfield and State of Connecticut, have jointly invented certain new and useful improvements in rail-chairs by means of which railway-rails are firmly secured to the wooden sleepers, 10 more especially where the flat-bottomed rail is used.

The objects of our invention are: 1st, to provide perfect safeguards against the upsetting of the rail; 2nd, to provide side supports of the rail; 3rd, to provide means which minimize the cutting of the rail in the tie; 4th, to provide a rail-chair which can be easily removed and replaced; 5th, to provide safeguards against creeping; 6th, to 15 provide a more efficient, simplified, and low-cost article; 7th, to provide safeguards against spreading of the gage of the track.

Other objects will appear from the hereinafter description.

25 The invention is a rail-chair having wedge shaped, double plates, one upon the other, of which the thin edges are in opposite directions, presenting when in place a uniform thickness of metal under the rail, 30 a flat surface against the tie, with the downward flange at the edge of the tie, and presenting a flat surface to the flat bottomed rail, a clamp space over the flange of the rail on both sides, and side supports to the 35 web of the rail.

When spiked to the tie in its effectual position and adjustments, our improved rail-chair is fastened to the tie by a spike through a hole in each end of the chair 40 through both plates, clamping the rail to the tie by a positive lock by means of the cut-away space in the braces, pressing the braces against the sides of the rail, and holding the rail from creeping by means of the flange 45 down the side of the tie.

In the accompanying drawings made part of this specification, Figure 1 is a perspective view of the rail-chair spiked to the tie, a part length of which is shown, and clamping a piece of a rail, showing in the whole 50 a complete rail-seat; Fig. 2 is a perspective view of the separate parts of the rail-chair; Fig. 3 is a transverse section of the rail-chair through the braces; Fig. 4 is a modi-

fication showing pairs of side braces, two 55 on each side of the rail.

A designates the rail-chair as a whole.

B is a side brace integral with the top, wedge shaped leaf C of the bottom of the rail-chair, so shaped on its under side as to 60 have a cutaway part b, which fits over the flange of the rail for the whole width of the flange when the brace is snug against the web of the rail.

B' is a brace, preferably smaller, integral 65 with the bottom wedge-shaped leaf C', having a cutaway space b' fitting over the flange of the rail.

The side braces B and B' may be in pairs on each leaf, as shown in Fig. 4.

C is the top wedge shaped leaf of the rail-chair; C' is the bottom leaf thereof; D is a wide tongue of the wedge shaped leaf C', and E is a slightly wider groove in the top leaf C, wherein the tongue D fits and slides. 70 D' is a narrower tongue of the top leaf in the modified form shown in Fig. 4. E' is a narrower groove in the bottom leaf, adapted to receive the tongue D', in which it slides. 75

F is a side flange on the leaf C, extending downward and adapted to fit against one side of the tie.

G is a tie or wooden sleeper of a railroad road-bed.

H is a railroad rail.

I is a hole through both the top leaf C and through the bottom leaf, C', registering when the leaves are in place at the rail-seat and the braces B and B' are snug against the sides of the rail.

K is a spike through the holes I into the tie G, firmly holding the leaves C and C' in their effective locking position, and fastening the rail-chair firmly to the tie.

In constructing railroads involving our improved rail-chair, the ties and rails are first laid in position; but instead of spiking the rail to the tie by the ordinary driven railroad spike or screw spike, the rail is 100 slightly pried up from the tie and the top wedge-shaped leaf C inserted from the outside of the rail, between the rail and the tie, and the bottom leaf C' inserted under the top leaf C from the inside of the rail, 105 and the two driven together until the side braces B and B' are snug against the web of the rail. The holes I through both leaves

C and C', then register, and a spike is driven through each pair of holes into the tie, whereupon the construction is complete. When adjusting the plate, the flange F is placed snug against the side of the tie, and the flanges on other chairs are placed on the other side of the tie, so that the clamped rail cannot move lengthwise without dragging the tie, and thereby the creeping of the track is prevented, or lessened.

In derailing accidents, where rails are spiked directly to the ties, it is readily seen that when the trucks of a passing train are swaying from side to side, the flange of the wheels may lunge against the inside edge of the head of a rail, tending to upset the rail outward, and putting the stress on the inside spikes in a direction to draw the spikes; and this is the weakest spot in roadbed construction. By our improved rail-chair, we put this stress against the outside larger brace. Against this the rail cannot upset, unless the outside spike is sheared off, and we thus transfer the force in operation from a drawing stress on the inside spikes, to a shearing stress on the outside spikes, and the latter offers manyfold greater resistance to this stress than the former.

We do not confine ourselves to the details of construction, but have described our improvement in its best form, but by way of illustration, and not by way of limitation. For example, without showing all the variations, we may omit the groove and tongue wherein the wedge-shaped leaves fit, and may make the bottom leaf as wide as the top leaf; and we may make the leaves flat instead of wedge shaped, and may make the side braces the full width of the top leaf or less, and may make the braces in pairs on both leaves, or on either; or may employ only one brace on each leaf, for whether the plates are wedge shaped or not, or move together in tongue and groove, when the side braces are brought up snug against the web of the rail, and the two plates are spiked to the tie through the holes I, the braces are locked against the tie and the strains are converted as hereinbefore de-

scribed; and thus we accomplish all the foregoing objects.

We may obtain the objects of our invention in some degree by omitting the holes I and spiking the plates at the edge, the same as a rail is now spiked direct to the tie.

By the use of our improvement, we reduce the shearing strain on the spikes and lag screws.

Having now described our invention, what we claim as new and desire to secure by Letters Patent is—

1. In a rail-chair, two wedge-shaped bottom plates, overlapping when in place, and adapted to be inserted at the rail-seat, the thin edges first, each carrying a clamp adapted to hold the flange of the rail, spike holes in each leaf which will register when the plates are in place, and adapted to receive spikes when in such position.

2. In a rail-chair, two wedge-shaped bottom plates, overlapping when in place, and adapted to be inserted at the rail-seat, the thin edges first, each carrying a clamp adapted to hold the flange of the rail, one of which clamps is also a side brace.

3. In a rail-chair, two wedge shaped leaves, a side brace on each, holes for both leaves, each adapted to receive a spike, and a side flange adapted to fit the side of the tie.

4. In a rail-chair, bottom plates having a wedge-shaped channel in one, and a wedge-shaped tongue in the other, adapted to be inserted at the rail-seat from opposite sides of the rail, each plate carrying a clamp adapted to hold the flange of the rail, one of which clamps is also a side brace.

In witness whereof, we have hereunto set our hands and affixed our seals, at Stamford, in the county of Fairfield, and State of Connecticut, this 9th day of April, 1912.

VAN BUREN L. HOYT. [L.S.]
ANDREW SAROSI. [L.S.]
ADNEY WOOSTER. [L.S.]
